UNITED STATES PATENT OFFICE.

MATTHEW R. HULL, OF CONNERSVILLE, INDIANA, ASSIGNOR TO REX MANUFACTURING COMPANY, OF CONNERSVILLE, INDIANA, A CORPORATION OF INDIANA.

CONNECTING MEANS FOR TWO-PART AUTOMOBILE DOORS.

Application filed March 29, 1924. Serial No. 702,956.

To all whom it may concern:

Be it known that I, MATTHEW R. HULL, a citizen of the United States, residing at Connersville, in the county of Fayette and State of Indiana, have invented certain new and useful Improvements in Connecting Means for Two-Part Automobile Doors, of which the following is a specification.

My said invention relates to an improvement in connecting means for two-part doors of automobiles or other vehicles and it is an object of the invention to provide simple and effective means for biasing the upper demountable section so as to bear firmly but yieldingly against the body of the car particularly at the upper and closing sides of the door.

Referring to the accompanying drawings, which are made a part hereof, and on which similar reference characters indicate similar parts—

Figure 1 is an elevation of the inner side of a door with my improvements applied thereto;

Figure 2, an end view of the connector detached from the door viewed from the right, and

Figure 3 a section on line 3—3 of Figure 1.

In the drawings reference character 10 indicates the outer panel of an upper demountable door section which has a sight opening as usual to provide a space for glass or other transparent material here shown as comprising two panes 11 and 12. The panel 10 is supported by a wooden frame 13 comprising upper and lower and side members surrounding the panes of glass. A sheet metal reenforcement 14 covers the frame members 13 more or less completely on three sides and preferably extends completely around the opening of the door, said reenforcement lying flat against the door at the top and bottom and being fluted at the sides to provide narrow vertical chambers beyond the side members of the frame in which chambers the ends 15 of the door connector 16 are removably positioned.

A securing member 17 is located between the panel 10 and the reenforcing member 14, this securing member being fastened to the demountable door section by rivets 18 which also pass through securing member 19 on the inner side of the door. The securing member 17 is bent so as to lie inside the permanent door section at its lower end

where it is provided with a slot registering with a hole in the member 19. A bolt 20 is inserted through said openings and the permanent door section and a screw 21 may, if desired, be located in a hole in the member 19 for more rigidly fastening the parts together.

The horizontal body of the connector 16 extends along the lower edge of the demountable section and near the closing side of the door has pivotally attached thereto a post 22 adapted to be positioned in a hole in the upper edge of the permanent door section.

It will be clear from consideration of Figure 2 that the connector is biased to throw the upper side of the door inward to a slight extent so as to cause this side to strike the door frame before the permanent door section is entirely closed whereby the body of the connector is twisted. In the present arrangement the torsion of the body of the connector also biases the closing side of the door in the same way so as to insure constant bearing of the removable door section against the door frame and do away with any rattling or rumbling noise caused by relative movement of the door and its frame. It will be understood that when the parts are being assembled the body of the connector will be twisted by bringing the ends into the same vertical plane, the strain falling on the relatively long body part of the connector and being distributed thereover. The upper demountable section of the door can very readily be removed when desired by withdrawing screws 20 and 21 after which the entire upper door section may be taken off the permanent section.

It will be obvious to those skilled in the art that certain changes may be made in the device without departing from the spirit of the invention and therefore I do not limit myself to what is shown in the drawings and described in the specification but only as indicated in the appended claims.

Having thus fully described my said invention what I claim is:

1. In a demountable door, a permanent lower section, a demountable upper section having sockets adjacent opposite sides, a connector having a resilient body with ends adapted to fit in said sockets said ends normally lying in diverging planes intersecting in said body and means for securing the

upper section to the lower section whereby the upper end of the upper section is biased toward closing position, substantially as set forth.

- 5 2. In a demountable door for vehicles, a permanent lower section, a demountable upper section, a connector having a resilient body with upwardly bent ends normally lying in diverging planes intersecting in said body said arms being adapted to be secured to the demountable door section in parallel relation to each other, means for attaching the demountable door rigidly to the permanent door at the hinged side, and
- 10 18 means for securing said parts together loosely at the closing side, substantially as set forth.
- 15 3. In a demountable door for vehicles, a permanent lower section, a demountable upper section, a sheet metal reenforcing member at the inner side of the door providing parallel sockets at its lower end, a resilient connector having upturned ends fitting in said sockets said ends normally lying in divergent planes whereby the upper door section is biased toward closing position at its upper and closing sides, and means for securing the said demountable section to the permanent section, substantially as set forth.
- 20 25 30 4. In a demountable door for vehicles, a

permanent lower section, a demountable upper section having sockets, a resilient connector rod having a body with parallel ends extending into said sockets said ends normally lying in diverging planes whereby the demountable section is biased at its upper side toward the vehicle body, a pin pivotally mounted on the body of said rod engaging a socket in the lower section, and securing plates on opposite faces of the demountable section adjacent the hinge side attached to said lower door section, substantially as set forth.

5. In a demountable door, a permanent lower section, a demountable upper section having sockets adjacent opposite sides, a connector having a resilient body with ends adapted to fit in said sockets said ends normally lying in diverging planes intersecting in said body and means for securing the upper section to the lower section whereby the free or closing side of the upper section is biased toward closing position, substantially as set forth.

In witness whereof, I have hereunto set my hand and seal at Connersville, Indiana, this 25th day of March, A. D. nineteen hundred and twenty-four.

MATTHEW R. HULL. [L. s.]
